United States Patent

Des. 236,095
Patented July 29, 1975

236,095

REFLECTOR

Gerald Golden, Highland Park, Ill., assignor to
Beatrice Foods Co., Elgin, Ill.

Filed Aug. 7, 1974, Ser. No. 495,401

Term of patent 14 years

Int. Cl. D10—06

U.S. Cl. D10—111

FIG. 1 is a front elevational view of a reflector embodying the design;

FIG. 2 is a rear elevational view of a reflector embodying the design;

FIG. 3 is a top plan view of the reflector illustrated in FIGS. 1 and 2;

FIG. 4 is a bottom plan view of the reflector illustrated in FIGS. 1 and 2; and

FIG. 5 is a side elevational view of the reflector illustrated in FIGS. 1 and 2.

The oblique line shading indicates a reflective surface.

I claim:

The ornamental design for a reflector, substantially as shown and described.
